CLAIM

The ornamental design for a bottle, as shown and described.

DESCRIPTION

FIG. 1 is a top perspective view of a bottle;
FIG. 2 is a top plan view of the bottle shown in FIG. 1;
FIG. 3 is a bottom plan view thereof;
FIG. 4 is a front elevational view thereof; and,
FIG. 5 is a left side elevational view thereof.

A rear elevational view is not shown because it is a mirror image of the front elevational view shown in FIG. 4. A right side elevational view is not shown because it is a mirror image of the left side elevational view shown in FIG. 5. The broken lines shown in the drawings are for the purpose of illustrating portions of the bottle and form no part of the claimed design.
